UNITED STATES PATENT OFFICE.

FRANCIS MORRISON, OF PHILADELPHIA, PENNSYLVANIA.

BOTTLE-STOPPER ATTACHMENT.

SPECIFICATION forming part of Letters Patent No. 634,697, dated October 10, 1899.

Application filed July 22, 1899. Serial No. 724,763. (No model.)

To all whom it may concern:

Be it known that I, FRANCIS MORRISON, a citizen of the United States, residing at the city of Philadelphia, in the county of Philadelphia and State of Pennsylvania, have invented a certain new and useful Bottle-Stopper Attachment, of which the following is a specification.

One object of the invention is to provide a simple, efficient, and reliable bottle-stopper attachment which may be used for measuring proper doses from the contents of the bottle and also as a means for taking the doses.

Another object of the invention is to prevent accidental leakage of the contents of the bottle when the same is, for example, packed in a trunk or other box for transportation.

Other objects of the invention are herein-after more fully described.

The nature, characteristic features, and scope of my invention will be more fully understood from the following description, taken in connection with the accompanying drawings, forming part hereof, and in which—

Figure 1 is a perspective view of a bottle-stopper attachment embodying features of the invention. Fig. 2 is a sectional view of the bottle-stopper attachment, illustrating the fact that an upward thrust is necessary for opening the valve; and Fig. 3 is a view, partly in central section, illustrating the invention in application to a bottle.

In the drawings, 1 is a receptacle, shown as of general pear-shaped form, and may be constructed to contain an appropriate dose of the contents of the bottle 2. This receptacle 1 is provided with an opening at each end, and at the lower end there is mounted or provided a stopper-body 3. In what I believe to be the best embodiment of the invention there are provisions, as shown, at the other end of the receptacle. These provisions comprise a valve 4, constructed and arranged to close an opening in the upper end of the receptacle 1, and a spring 5 or its equivalent, which holds the valve 4 in position for closing the opening in the top of the receptacle. The object of this construction is to make it necessary to lift the valve when required, which is a thing that is not likely to happen accidentally.

6 is a support or back-stop for the spring, and it may operate as a guide for the valve-

spindle, and it should be constructed so as not to exclude air under conditions that will be presently described.

The mode of operation of the described bottle-stopper attachment may be explained as follows: The parts occupy normally the position shown in Fig. 3, and under these conditions the stopper-body fits the neck of the bottle 2 and closes it, and the valve 4 is pressed by the spring 5 tightly to its seat and closes the opening in the top of the receptacle 1. Thus the contents of the bottle may not escape. As shown, the part 6 comprises a hood with air-openings 7. The valve 4 may be arranged to cover these openings, as shown in the figures. Thus the possibility of leakage is guarded against. To obtain a dose of the medicine, the bottle is turned upside down, with the result that the receptacle 1 fills, as indicated in Fig. 3. The stopper-body is then withdrawn from the bottle and the contents of the receptacle 1 discharged into any suitable receptacle by lifting up the valve 4—for example, by passing the finger under the operating-handle 8 of the valve, as shown in Fig. 2, and then lifting it up, thus permitting the air to enter the top of the receptacle, so that its contents will fall out. Among the many advantages of the described construction I may mention the fact that it is necessary to lift up the valve 4, as contradistinguished from pushing it down, whereby the accidental opening of this valve is guarded against, because it is very unlikely that anything could accidentally get under the operating-handle of the valve, and thus lift it, whereas it is most likely that a great many things would press down upon this handle—for example, it would probably be pressed downward in a trunk or other receptacle.

It will be obvious to those skilled in the art to which my invention appertains that modifications may be made in details without departing from the spirit thereof. Hence I do not limit myself to the precise construction and arrangement of the parts hereinabove set forth, and illustrated in the accompanying drawings; but,

Having thus described the nature and objects of my invention, what I claim as new, and desire to secure by Letters Patent, is—

A bottle-stopper attachment comprising a receptacle open at each end and having one

of its ends equipped with a stopper-body and having its other end equipped with a valve, a spring arranged to press said valve toward the receptacle to normally close its corresponding opening and a handle operatively connected with the valve and adapted to open it when pushed upward, substantially as described.

In testimony whereof I have hereunto signed my name in the presence of two witnesses.

FRANCIS MORRISON.
